UNITED STATES PATENT OFFICE

JAY M. MULLIN, OF ELMHURST, NEW YORK

DESIGN FOR A COMBINED BOOKCASE, CLOCK CASE AND RADIOCABINET

Application filed February 24, 1931. Serial No. 38,798. Term of patent 7 years.

To all whom it may concern:

Be it known that I, JAY M. MULLIN, a citizen of the United States, residing at 85-35 Britton Avenue, in the city of Elmhurst, county of Queens and State of New York, have invented a new and original Design for a Combined Bookcase, Clock Case, and Radiocabinet, of which the following is a specification, reference being had to the accompanying drawings, forming part thereof.

Figure 1 is a front elevational view of a combined bookcase, clock case and radiocabinet, showing my new design; and

Figure 2 is a side elevational view of the same.

The small panel, or opening in the upper

part of the first or base section, is for the radio controls. The grilled panel in the second or middle section is for the passing of sound from the radio loudspeaker and to conceal the bookcase section. The small panel, or opening in the upper part of the second or middle section, is for the radio dial. The small panel, or opening in the upper part of the top or clock section, is for a magnetic thermometer.

I claim:

The ornamental design for a combined bookcase, clock case and radiocabinet, as shown and described.

JAY M. MULLIN.
